UNITED STATES PATENT OFFICE.

LOUIS R. LEMOINE, OF PHILADELPHIA, PENNSYLVANIA.

TRAVELING-CRANE MECHANISM.

SPECIFICATION forming part of Letters Patent No. 431,000, dated June 24, 1890.

Application filed February 14, 1890. Serial No. 340,501. (No model.)

To all whom it may concern:

Be it known that I, LOUIS R. LEMOINE, of the city and county of Philadelphia, State of Pennsylvania, have invented a new and useful Improvement in Traveling-Crane Mechanism, of which the following is a true and exact description, reference being had to the accompanying drawings, which form a part of this specification.

My invention, in general, is well adapted and contrived for combination with such overhead-traveling bridge-cranes as have their movable "working" part or parts (bridges, trolleys, and hoisting and lowering or "lift" mechanism) actuated one or all from one or more relatively fixed prime movers or engines, whether steam, hydraulic, or what not, said engines being equipped with transmitting and regulating devices (say lines of shafting or wire ropes and valves, throttles, &c.) and their immediate gear. However, it being especially applicable to such of these cranes as in the more recent developments thereof are actuated by one or more fixed hydraulic ram or rams, it is hereinafter more particularly described in that connection as its most apt mode of illustration rather than as thereby particularly limiting its scope.

More especially my invention relates to the framing and mechanism that transmit the crane-driver's movements of control to the regulating devices of the motor mechanism of such overhead-traveling cranes, as well as define the position or positions assumable by the crane-driver in manipulating the same; but in order to more clearly disclose the field within which my invention lies it will be necessary, before passing to the illustrative description thereof, to state that heretofore overhead-traveling cranes have usually been operated with more or less success in one or other of the following ways, viz: first, either from a fixed "pulpit," as it is called, in which—much after the manner of a railway-switchman in an interlocking switch-tower—the crane-driver, usually by throw-levers, or, if at a distance, by pull-cord, shipper-bars, &c., controls the belts, clutches, &c., of the transmitting device's connecting-gear or the valves or conduit-throttle, brakes, &c., of the crane-motor itself, and so produces the desired change, whether from rest or motion, or when in motion, in direction, velocity, &c., in the actual working parts of the crane; second, otherwise, and especially where the range of travel is great, the approved practice has been to carry upon or suspend from the crane's traveling bridge a cage. In this the crane-driver is carried, and to it are operatively connected the mechanisms which serve to transmit his movements of control to the prime mover or to its force-transmitting mechanisms, thus causing them to be brought in or out of gear with the crane's working parts, and so to start, stop, reverse, &c., the same, or, third, from the floor of the foundry or other building or place where the crane may be erected. Now, these fixed pulpits and bridge-carried cages subject the crane to evils, some of which they share and some of which evils are peculiar to the enjoyment of one or other of these devices, so that to rely on one as the antidote for the ills of the other's practice is but to seek the second horn of a dilemma, viz: If the pulpit be the theater of control and the range of bridge travel be great, it may well be that, despite the central or mean location of the pulpit between the termini of said bridge's travel, intervening mechanism, &c., of the shop or yard in which the crane is located may obscure the crane-driver's view, or else the distance to which the bridge has gone (half or less, though it be, of its total travel) is yet so great as to make the crane-driver's vision of its workings unreliable. Thus predicted his resource becomes "conning" by assistants, who shout or signal directions as to the "travel" of the bridge, the "traverse" (lateral movement) of the trolley, or the hoisting or lowering of the crane lift or purchase-tackle, and so, by the variety of the duty as well as the distance intervening and the multiplicity of minds and signals involved, there arise in practice frequent cases of miscontrol, and from these flow accidents to the crane or its load and at times loss of life or limb to its attendants. So, too, with the bridge-carried cage, the crane-driver is here often borne, "will he, nill he," in or out of view of the place where or machine on which he wishes to take up, remove, or carry to and place his crane's load; and this sort of caged control,

while it automatically brings the crane-driver from any starting-point on the craneway, however distant, and keeps him always near his load, (where he can the better hear and see signals that are to "con" him,) yet it more frequently than the pulpit, by reason of the cage's elevation and close proximity to the bridge, fetches the crane's load between him and the place or machine on or to which he is to divert or apply it. Moreover, the usual transmitting device to the motor's throttle or belt-shipper, &c.,—a pull-cord led by guide-pulleys to and through the bridge-carried cage—also to a great extent offsets and viatates the advantages which such close associations with the bridge may give, for if the movement of control which the driver desires to impart to it be in the direction in which the bridge to which his cage is attached is then going it becomes very difficult for him to impart a precise amount of motion, or any, without a jerk. Again, in traveling in the opposite direction there is a change of conditions, and experience gained from motions of control made in one direction of cage travel is but of little use for controlling when traveling in the opposite direction. So a third condition—that of rest—produces still greater confusion, and thus the driver is, between the signals of his assistants and the vices of his apparatus, in a vexatious position, and while electric and pneumatic transmitting devices may be employed to relieve the structure from these latter ills by reason of their flexibility, and the slack conditions in which their conduits may act, these devices are more elaborate, require greater care, and are, compared with the pull-cord or equivalent positive connection between the regulator and crane-driver's manipulating point, of uncertain and complicated character, and so less desirable. Moreover, if led to a bridge-carried cage, even such flexible slack-transmitters in no way assist the crane-driver to an unobstructed side-wise view of what he is doing with the crane's load, and, finally, the leading to and passage of an operating pull-cord along or in close proximity to the floor over which the crane ranges, as above alluded to in the third of the enumerated ordinary ways of putting the crane-driver in connection with the controlling "in-and-out-of-gear" connections, is so obviously subject to the criticism of being hopelessly in the way, inartificial, and inapplicable to shops and places which have traveling-crane plants that, dismissing it summarily, I now state, without further recitation of existing evils, that my invention, broadly speaking, consists, first, in giving to the crane-driver a gallery, gangway, or free passage substantially coextensive with the range of bridge-travel, and, preferably, also with that of the "traverse" (bridge-crossing movement) of the trolley, along which gangway the crane-driver can range independently of a fixed single pulpit-station or a bridge-carried cage; second, in equipping such gallery, whose location is

to be the best which the circumstances of construction, location, and association with other structures will permit of for a general clear observatory, with a diffused mechanism for control, which mechanism may be so fashioned as to be a single mechanism coextensive with the thus extended range of the crane-driver, or of a systematically-distributed series of mechanisms of manipulation and control ranged along it at convenient intervals; and, referring now to the illustrative case—

Figure 1 is an end elevation, given partly in section and interrupted, of a hydraulically-actuated overhead-traveling crane embodying my invention. Fig. 2 is a plan view of a fragment of the structure shown in Fig. 1, the parts omitted being the transverse gallery and motor mechanisms. Fig. 3 is a diagram showing in plan the location and rigging of the preferred system of hydraulic hauling and lift mechanisms for the crane illustrated in Figs. 1 and 2, as well as itself illustrating a modification, wherein two bridges are so equipped and arranged tandem-wise upon the same line of overhead ways. Fig. 4 is also a diagram showing in plan the location and rigging of the preferred dual system of hydraulic-ram trolley-traversing mechanisms for the said crane and tandem modification thereof. Figs. 5 and 5^A are respectively an end and a side elevation of a modification; Fig. 5^B, a cross-sectional detail of a reducing-valve upon an enlarged scale. Fig. 6 is a diagram illustrating in side elevation the preferred relative location of the main operating-gallery, with its equipment of controlling mechanism, the adjoining overhead way, and a bridge end and bridge-hauling ram. Fig. 7 is a perspective view of a fragment, showing a modification of the operating-gallery's motor-controlling mechanism; also, an adjustably-securable gallery-supporting bracket. Figs. 8 and 9 are respectively side and end elevations of a preferred form of manipulating device for a motor-controlling station upon the operating-gallery. Fig. 10 is a modification wherein the gallery-controlling mechanism is transmitted, and leads to a valve-center isolated from the motors it regulates. Fig. 11 is a fragmentary interrupted diagram in plan to illustrate the preferred grouping and distribution of a series of gallery-operating stations for a two-bridge tandem crane; also, by its solid lines, this figure shows a more restricted gallery range, while its dot-and-dash outline denotes a completely continuous marginal operating-gallery. Fig. 12 is a central fragment in end view of a further modification, wherein two parallel and adjoining or duplex overhead cranes have an intermediate common operating-gallery.

In general, in the figures, O O are the overhead ways; o o, the columnar supports thereof; B, the bridge spanning the ways and adapted to run lengthwise thereon upon truck-wheels b b b.

T is the trolley, of which t t t are the truck-

wheels, for which the bridge across tracks O' O' afford a traverse guideway.

E is the lift-fall block, whereof *ff* are the sheaves and *f'* the hook.

5 S is the bridge-squaring shaft, which, by means of the racks *ss*, (see end sections thereof, Fig. 1,) lying parallel and close to the ways O O', the rack-engaging pinions *s' s'*, rotatably journaled to the inner sides of the 10 bridge-truck brackets S' S', and said shaft's fixed terminal pinion-intermeshing spur-wheels *s² s²*, transmits whatever lateral movement may be developed at one end of said bridge equally to the other.

15 G is the operating-gallery, which, in the crane illustrated in Fig. 1, is extended not only along the whole of one side of the overhead-way supports, but also across one end of said ways. This gallery may, however, be of 20 less or greater extent (see Fig. 11) without departing from the spirit of my present invention, and if, as in said latter figure, it affords a range of operating positions independent of the bridge or bridges of the crane 25 a single gallery may serve for controlling two bridges, &c.; or even, as illustrated by the fragment shown in Fig. 12, but a single gallery may be located intermediate to the two adjoining parallel overhead ways of a duplex 30 crane. In construction I prefer to fashion this gallery as shown in Figs. 1 and 2—viz., of a footway or grating *g*, hand-rail *g'*, supported by brackets *g² g²*, said supports being either permanently secured to the overhead 35 ways at such relative height as might just afford head room beneath the bridge to the operator, and in this respect I also preferably secure it thereto with vertical adjustability. This further preferred modification is illustrated in Fig. 7, where a gallery-bracket is 40 shown having eye-sockets *g³ g³* and a set-screw *g⁴*, whereby it might be attached at any desired altitude on the shaft of the columnar overhead-way support *o*, along which its said 45 sockets are otherwise free to slide. To adapt the other chief element of my invention to such adjustability of the gallery, I contrive that the vertical connections between the shipper and the part it controls shall be susceptible of the like adjustability. This is also 50 illustrated in Fig. 7, where a rocking shipper *w⁹* carries a toothed sector *Q'*, which, on being intermeshed at any desired altitude upon the rack-work *w¹¹* of the valve-gear, connected pitman *w¹⁰*, afford such operative connection with a motor-regulator as my present invention demands. However, before passing to the 55 details and modifications of the shipper and its connections, the motor mechanism of the sort 60 of crane to which my invention is especially applicable should be first briefly described to make the combinations which I effect therewith clear. Said motor mechanism consists of a system of hydraulic rams, the rams of which 65 are severally equipped with, first, supply and escape conduits, designated *c* and *d*, respectively, connecting them (the rams) with ac-

cumulator or water-head conduit C and waste-water drain D, (see Fig. 1;) second, valves *V* and their immediately-associated valve-gear *U*, constituting the "regulating" devices of the said rams, and preferably, also, though it is only so illustrated at *V'*, Fig. 5^B, with reducing-valves controlling the area of the supply-conduits, which valves serve, on being moved, 70 to correspondingly modify their rams's plunger speed, for these valves, having a limited amount of movement permitted to them—as by the adjustably-protruded abutment screws shown at either end of the valve-lever's arc-shaped yoke in the example, Fig. 5^B—are, as is readily understood, and, therefore, not further explained, contrived never to wholly cut off the supply, but merely operative when thrown to one side or other, as shown, to reduce the area or "gate" opening from the main conduit, to which, when in their intermediate or normal position of lever, they offer no restriction whatever; third, as a force-transmitting mechanism, with tackles, consisting of relatively fixed and ram-plunger-carried pulleys *P P* and *P' P'*, respectively, over the sheaves *p p* of which pulleys a wire rope or ropes *h' t' r* after being passed is at one end made fast or anchored, and the other, 80 as a whip or "running part," carried from such speed-generating, or, as it generally is called "invented rigging," to and over guide-pulleys *p²*, that lead it to the movable part, (bridge, &c.,) to which such particular rope's 85 motor is attached, as hereinafter described. Now, said actuation of the movable working parts—apart from the crane-driver's control through the gallery-led shipper device, the description of which latter is postponed to the 90 present, as it were, introductory and explanatory matter—is, in said crane, accomplished as follows:

First. For the travel of each bridge or bridges—for there may be more than one—by 110 locating at either terminus and at equal and near distances from the same side of the overhead way, a pair of equal single-acting and vertically-disposed hydraulic rams *H H*, (see Figs. 1 and 3,) the hauling ropes *h h* of 115 whose tackle have their aforesaid running ends passed vertically upward over a guide-pulley *p²*, and thence carried to and attached opposite each other, as by the eyebolts *b' b'*, fixed to the side body of the bridge; for, although these ropes are applied unilaterally, the bridge-squaring mechanism *S s² s' s' s s*, above described, prevents binding and causes the bridge to preserve a correct alignment.

Second. For raising and lowering the lift-fall block E of such bridge or bridges a single ram *R*, of substantially similar disposition and equipment to either of bridge-hauling rams *H H*, is located near to one or other of said latter rams. Its rope's (*r*) running end 125 being led by another adjoining guide-pulley *p²* is thence forwarded to a vertically-pivoted bridge-carried pulley *p⁴*, and thereby passed inward and crosswise upon the bridge B to a 130

horizontally-pivoted trolley-borne guide-pulley p^5 , thence downward under the first fall-block sheave f , again upward and over trolley-pulley p^6 , which leads it in a prolongation 5 of its former course upon the bridge to the opposite end thereof. Thence this hoisting-rope (or ropes, if more than one be used, as is the best practice for safety) is then by pulleys p^8 p^9 p^{10} passed parallel to its former or ingoing 10 course, and so outward to and in a prolongation of its original overhead way route outward and made fast to an anchor J , located at or rather just beyond the further terminus of the overhead way O .

15 Third. For traversing the trolley T single-acting paired rams $T' T'$, acting in opposition, are employed. These, for economy of floor room, are placed horizontally in line with the ways $O O$ upon the superstructure, but 20 at adjoining opposite corners thereof. Their equipment of conduits, valves, and inverted purchase-rigging, being substantially similar to those of the hauling and lift systems aforesaid, save the running part t' of their 25 rigging passing directly forward to the bridge end, is there run in loops about three guide-pulleys p^{11} p^{12} p^{13} , pivoted vertically to the bridge and trolley ends, respectively, as shown in Figs. 1, 2, and 4, and then each passed on- 30 ward coextensively along the adjoining overhead way to an anchorage J' , opposite the rams from which they respectively originated.

Now, resuming the description of the crane-driver's motor - controlling mechanism, the 35 gallery G contrived and extended, as above described, about the crane. I further equip for the purpose of affording the crane-drive means of controlling such a system of motor mechanism or its equivalent whether said 40 gallery applied to cranes having a single bridge or two or more bridges arranged tandem-wise or in adjoining duplex cranes, preferably as follows: With a longitudinally-extending endwise-movable shipper such as 45 either of the wires $w w' w^2$, Fig. 1, which severally repose upon the sheaves of guide-pulleys W^{10} , located at convenient intervals along the gallery hand-rail, and so extend not only 50 coextensively along it, but, as by other terminal guide-pulleys W^{10} , are passed therefrom to the valve-stem v or other ordinary immediate valve-controlling gear U , with which the 55 motor is regulated in its movements and arrests, the slack of such wire being taken up and its quick response to the driver's actuation being promoted by the device of auxiliary tension-cords w^4 , spliced to or branching from the ends of the horizontal runs of the 60 shipper part proper, said tension-cords being attached to depending counterpoise weights W^3 W^3 . (See Figs. 1, 5, and 6.) Otherwise, instead of a wire or flexible pull-cord, a 65 rigid throw-rod or shipper-bar, as w^{10} , Figs. 5 and 5^A, may be employed, and, as by the "bell-crank" w^{19} and pitman-links w^{11} , Fig. 5, operatively and positively connected to the valve or valve-gear of the ram or other

motor. So, too, as another modification illustrated in Fig. 7, the driver's movements of control may be transmitted from any point along 70 the range of the gallery G , by equipping its guard-rail stanchions with bearing-apertures M and intermediate tubular bushings M' , a square or polygonal rock-shaft w^9 , said shaft carrying at a proper part a device like the 75 toothed sector Q' , for intermeshing with the rack-work w^{11} of a pitman-link pivoted to, say, the hauling-ram valve-gear U , for said shaft w^9 by its polygonal cross-section affords a fair and ready bearing at any part for a 80 manipulating wrench or key K , and by it may be actuated at any place along the gallery of the crane; also, without departing from the purview of my invention, such flexible and easily dirigible transmitting devices, even as 85 electric or pneumatic conduits, (say, copper wire and india-rubber tube, respectively,) may be employed by simply carrying their operating ends equipped with their respective and ordinary manipulating devices to any 90 part of my gallery and there employ them to transmit the crane-driver's movements of control to electrically or pneumatically actuated valve-gearing, &c. Indeed, it here need only be added that while any of such mechanisms 95 may be employed to effect control at a plurality of points along the gallery I prefer the more positive mechanical sort, such as I have just given typical illustrations of; and also, that I prefer to provide such positive ones at those 100 points upon the gallery which convenience and experience suggest as the most frequently assumed by the crane-driver with fixed manipulating outfits, as stations. Such outfit is illustrated in Figs. 8 and 9. Here the function of 105 the throw-levers $L L' L^2$, each one of which is pivoted to a gallery-gudgeon N at its lower and T -shaped end $l' l'$, is on being rocked from a central or mean position forward or back, as indicated in broken lines, to depress 110 one and raise the other of their pivoted drag-links $l l$, and these by their further pivotal connections to the shaft fixed cranks $c' c' c'$ to thereby correspondingly rock their shippers $w^{20} w^{20} w^{20} w^{20} w^{20} w^{20}$ in pairs, this 115 paired arrangement being preferred because it is desirable in the illustrated case to be thus able to actuate either, first, the supply and escape valves of a single unpaired ram-motor, as that of the lift R , simultaneously 120 and in opposite direction—that is, one closing as the other opens, and vice versa—or, second, and in similar simultaneous fashion, the supply and escape valves of the 125 jointly-acting, yet widely-distant, paired rams, such as those of the bridge and trolley systems—viz., of rams $H H$ or $T' T'$ —for both of which purposes the opposite, yet equal, angular throw produced in the shipper-shafts $w^{20} w^{20}$ on any movement of their connected 130 lever-handle L is manifestly well adapted, their connection to the valves being, say, by such gearing as the toothed sector Q' and pitman-rack. (Shown in Fig. 7.) Also, de-

spite some loss in the nicety with which such outfits when they are used enable the crane-driver to impart his movements, such concurrent actuation, even of such widely-separated motors as the bridge-hauling rams H H, Fig. 3, may also be effected by terminal attachment of unelaborated gallery-passed shippers—say the pull-cords *w*—for which purpose the ends of any one of which shippers, being led and secured to the supply and escape valves, respectively, of paired rams, serves to connect at least that pair's valves conversely and operatively. Moreover, if such shipper's connection with the ram-regulator be by a suitable intermediate linkage, such as that illustrated in Fig. 1, (a weighted rock-lever *u*, pivoted intermediate to valve-stems *v v*, to which it is also pivotally connected,) each end of a single shipper may control a plurality of valves; but if equipped with lever-outfits, as above illustrated, the intermediate or vertical position of each hand-lever, as shown in Fig. 8, is advisedly selected for the one for the levers to assume when they (through their transmitting shipper-connections then offering to the opposing rams of each pair equal valve-openings) shall maintain the working parts connected therewith in equilibrium. For the constant tension thus produced and continuously maintained in all periods of rest throughout the force transmitting and moving parts of the bridge, traveling and trolley traversing systems materially aids the starting of them in either direction with both quickness and freedom from jerk, and thereby renders bridge and trolley movements entirely sympathetic with their shipper-lever's throws. Moreover, while the lift-ram *R* is a single one, it is to be remembered that with it the weight of the fall-block alone is generally sufficient to keep not only its rigging taut, but also to run back any protruded portion of its plunger in response to the opening of its escape, and that a lifted load of any sort further increases such state of affairs, and, in point of fact, acts "in opposition."

Of course the rams of the crane may be contrived to be double-acting and arranged to rotate a winding-drum instead of fall-tackle, or even transmit their force by shafts and gearing to the moving parts; but such modification being of detail not essential to my present invention need not here be described, and pointing out, first, that in Fig. 11, *Z* denotes the equipment of a two-bridge tandem crane's operating-gallery *G*, with an operating outfit

and transmitting or shipper mechanism wherever it occurs for one of the bridges, &c., thereon, and *Y* a similar station, &c., for the other bridge thereof; and, second, that in Fig. 12, *Z* and *Y* denote similar stations and equipment for the intermediate gallery of a duplex crane.

I now conclude by stating that what I desire to secure by Letters Patent of the United States, and hereby claim, is—

1. In an overhead-traveling crane, the combination of an elevated operating-gallery and a shipper device or devices operative from along said gallery, substantially as and for the purposes hereinbefore described.

2. In an overhead-traveling crane, the combination of the overhead ways, a stationary motor mechanism, a motor-regulating device or devices, an operating-gallery, a shipping device or devices operatively connected to and passing from said motor-regulating device or devices, and a plurality of manipulating devices for each of said shipper device or devices arranged at intervals in a series along said gallery, substantially as and for the purposes hereinbefore described.

3. In an overhead-traveling crane, the combination of the overhead ways, a pair or pairs of stationary motors, the individual members of which pair or pairs being adapted to work in opposition, as described, a motor-regulating device or devices for each individual motor of said pair or pairs, and a shipper device or devices operatively connecting the said motor-regulating device or devices in converse paired connection, and thence extended to and throughout an operating-gallery bordering said crane's range of transportation, substantially as and for the purposes hereinbefore described.

4. In an overhead-traveling crane, the combination of an overhead way, a movable working part mounted thereon, a hydraulic motor-ram operatively connected to said working part, as ram *H*, said ram having conduit and drain, a ram-regulating device consisting of supply and escape valves, an operating-gallery bordering upon said working part's range of action along said overhead way, and a shipper device operatively connecting said valves with said gallery, substantially as and for the purposes hereinbefore described.

LOUIS R. LEMOINE.
